(57) **CLAIM**

The ornamental design for a cable organizer, as shown and described.

DESCRIPTION

FIG. 1 is a perspective view of a first embodiment of a cable organizer showing my new design;

FIG. 2 is a front view thereof;

FIG. 3 is back view thereof;

FIG. 4 is left side view thereof;

FIG. 5 is right view thereof;

FIG. 6 is a top view thereof;

FIG. 7 is a bottom view thereof;

FIG. 8 is a perspective view of a second embodiment of the cable organizer;

FIG. 9 is a perspective view from below thereof;

FIG. 10 is a front view thereof;

FIG. 11 is back view thereof;

FIG. 12 is left side view thereof;

FIG. 13 is right view thereof;

FIG. 14 is a top view thereof;

FIG. 15 is a bottom view thereof;

FIG. 16 is a perspective view of a third embodiment of the cable organizer;

FIG. 17 is a perspective view from below thereof;

FIG. 18 is a front view thereof;

FIG. 19 is back view thereof;

FIG. 20 is left side view thereof;

FIG. 21 is right view thereof;

FIG. 22 is a top view thereof;

FIG. 23 is a bottom view thereof;

FIG. 24 is a perspective view of a fourth embodiment of the cable organizer;

FIG. 25 is a perspective view from below thereof;

FIG. 26 is a front view thereof;

FIG. 27 is back view thereof;

FIG. 28 is left side view thereof;

FIG. 29 is right view thereof;

FIG. 30 is a top view thereof; and,

FIG. 31 is a bottom view thereof.

(Continued)

The first embodiment of the cable organizer in FIGS. 1-7 is shown with a symbolic break in its length, and appearance of any portion of the cable organizer between the break forms no part of the claimed design. The cable organizer is understood to replicate between two ends in a manner that is consistently shown in subsequent embodiments.
